Patented Feb. 21, 1922.

Inventor
Charles G. Palmer
By his Attorney
Frederick C. Fischer

UNITED STATES PATENT OFFICE.

CHARLES G. PALMER, OF NEWARK, NEW JERSEY.

TOY PISTOL.

1,407,166.

Specification of Letters Patent. Patented Feb. 21, 1922.

Application filed March 2, 1921. Serial No. 449,098.

To all whom it may concern:

Be it known that I, CHARLES G. PALMER, a citizen of the United States, residing in Newark, in the county of Essex and State 5 of New Jersey, have invented certain new and useful Improvements in Toy Pistols, of which the following is a specification.

The principal purpose of this invention is to provide a toy pistol simulating in appearance real pistols and capable of detonations.

A further object is to provide means for automatically recocking the trigger and for advancing the detonator bearing strip into 15 operative position at each full movement of the trigger.

Another object is the provision of means whereby all of the several parts operate smoothly, easily and positively upon actuation.

These and other like objects, such as economical construction, durability of parts and ease of manipulation, are attained by the novel design, construction, combination 25 and arrangement of parts hereinafter described and shown in the accompanying drawings, forming a material part of this disclosure, and in which:

Figure 1 is a side elevational view showing 30 the interior of the piston, the cover portion being raised and the mechanism in a normal position ready for operation.

Figure 2 is a similar side view, the cover element being closed and broken away to 35 disclose the interior, the parts being in retracted position as just prior to discharge.

Figure 3 is a transverse sectional view taken on line 3—3 of Fig. 2.

Stated briefly in general terms, the pistol 40 consists of a pair of opposed side elements, hinged at their juncture at the top and engaged by a spring clip at the bottom of the handle portion.

The lock mechanism is carried on a plate 45 fixed in the body and comprises a spring actuated bolt retracted by a trigger and automatically released at the limit of the trigger movement.

Within the hollow handle is a coiled strip 50 carrying spaced detonators, this strip being advanced to bring a fresh, unused detonator into position to be struck by the bolt, at each full movement of the trigger, which is operated in the usual manner and automatically 55 returned to its initial position.

Referring now more specifically to the drawings in detail, the numerals 10 and 12 designate the respective sides of the pistol body, the same having curved marginal flanges 11 and 13 extending towards and 60 matching each other as shown, the whole forming a structure simulating in general appearance a real pistol of conventional pattern.

The flanges constituting the upper part 65 of the pistol body and barrel are connected by hinges 14, while at the butt of the handle is a spring slip 15, operating between guide lugs 16 by which the sides are held in engagement.

Secured against the inner side element 10 is a plate 18 pierced to receive lugs 19 extending in from the side and which are clenched tightly over forming secure fastening for the plate 18.

The upper portion of this plate is formed 70 into an elongated rectangular casing 20, disposed adjacent and parallel with the upper flanges of the side elements and suited to guide the hammer bolt 21 slidably contained therein, and provided with a striking head 22, the body of the bolt being otherwise hollow.

The inner side 20' of the casing 20 does 75 not make contact with the plate 18 but presents an open longitudinal space through which extends a projection 24 formed with the bolt or plunger 21, the front edge of the projection being turned slightly upward, for a reason further on apparent and inclined 90 outwardly or away from the head 22, forming a ledge 25.

Approximately centrally of the plate 18, near its lower edge, is set a fixed stud 27 having an enlarged head, holding in position a 95 trigger 28, the same being made of a single blank folded to present a pair of spaced sides 30 and 30' blending into a smooth face adapted to receive the finger of an operator.

Both sides of the trigger are pierced by 100 transverse slots 31, through which the body of the stud 27 passes and surrounding the stud, between the trigger sides, are the coils of compression spring 32, one of its extending arms 33 pressing against the inner side 105 of the trigger, tending to move it outwardly, while the other end 34 abuts against a lug 35 upturned from the extreme lower edge of the plate 18, the lug making contact with the flange of the side element in such man- 110

ner as to prevent displacement of the spring arm, and the movement of the trigger, which extends outward through the lower flanges of the side elements, is limited by stops 36 5 and 37 respectively front and rear.

The rear edge 39 of the plate is turned upward at a right angle and extended to pass outward above the upper flanges 11-13 through openings 38, the upper end 10 of the element 39 acting as a sight in connection with the hinge elements.

The element 39 also acts as an abutment or anvil for the striker head 22, and further, as a guide for a strip 40 of material 15 carrying the detonators, this strip, when coiled, as at 41, being positioned in the butt of the handle.

An offset arm 42 extends from the trigger element 30 its end being bent at a right angle 20 downward constituting an impeller 44 adapted to engage the ledge 25 of the bolt projection when the trigger is pulled, thereby retracting the bolt against the tension of a spring 45 coiled about a pin 46 fixed in the 25 plate 18, one of the spring arms 47 engaging the bolt 21 while the other arm 48 makes contact with a lug 49 formed from the plate 18, the spring operating to propel the bolt rearwardly and cause detonations to occur.

The top of the lug 49 is curved and adapted to make contact with an offset portion 50 formed on the trigger arm 42, causing it to spring slightly outward and release the impeller 44 from the ledge 25, whereupon the 35 bolt snaps against the strip under the impetus of the spring 45, and upon the trigger being released the impeller 44 glides over the elements 24 and 25 under the tension of the spring 32 to its normal position.

Another arm 52, formed with the trigger element 30 is given a right angle twist near its outer end, constituting a pusher 53 40 adapted to feed the strip 40 when the trigger is pulled, the trigger moving rearwardly due 45 to its slotted engagement with the stud 27 on which it also pivots, thereby raising the strip by sliding it along the surface 39 while retracting the hammer bolt.

At the moment of discharge, the bolt is 50 propelled rearwardly, coming into violent contact with the detonator carried on the strip over the face of the anvil 39 and clamps the strip during the return to initial 55 position of the trigger and pusher carried by it.

Thus the strip is extruded at each full movement of the trigger, the extending length of used material being torn off over the edge of the sight portion of the element 39.

In pulling the trigger the pusher first makes contact with the strip at a point below the axis 27 and is thus rotated upward on the axis, the strip being held by the 60 pusher under the pull transmitted through

the trigger and the spring 45 through the bolt and its extension until released, whereupon the spring 32 returns the parts into position for further operation.

As all contact points are smoothly curved 70 there is no catch or jerkiness in operation, but a smooth, uniform and easy actuation is obtained together with the several objects set forth.

While certain preferred embodiments of 75 this device have been shown and described, it will be understood that changes in the form, arrangements, proportions, sizes and details thereof may be made without departing from the scope of the invention as 80 defined in the appended claims.

Having thus described my invention, what I desire to secure by Letters Patent and claim is:—

1. A toy pistol comprising a hollow body, 85 a plate mounted therein, a guideway formed with said plate parallel to the pistol top and an abutment at an angle thereto formed with said plate, a spring impelled hammer slidably in said guide way contactable with 90 said abutment, a projection on said hammer, a spring returned, manually actuated trigger having a variable fulcrum on said plate, a resilient arm carried by said trigger engageable with said projection, and means for 95 automatically releasing said arm at the full operation of said trigger.

2. A toy pistol comprising a hollow body, having two hinged sections, a plate secured to one of said sections, a guide way formed with said plate parallel to the pistol top, a post fixed on said plate, a spring pressed trigger having a transverse slot engaged by said post, said trigger being movably pivoted thereon, a vertical abutment formed 105 with said plate extending above said body, its upper edge constituting a sight, a strip of detonators in said body movable over said abutment, feeding means for said strip carried by said trigger, a hammer normally 110 spring impelled against said abutment, said hammer, being slidably guided in the guide way formed in said plate, means carried by said trigger for retracting said hammer, and means for releasing said hammer upon completing the rearward movement of said trigger.

3. A toy pistol comprising a hollow sectional body, a plate secured therein, a headed post fixed on said plate, a trigger limitedly 120 bodily movable on said post lengthwise of said body and also pivoted thereon, a resilient arm formed with said trigger, said arm having an offset portion and an angularly turned end, a spring impelled hammer plunger slidable in a portion of said plate, an extension on said plunger engageable with the end of said arm, and a cam projection on said plate contactable with said offset portion of said arm whereby it is 125 130

raised and said projection released when contact is made irrespective of further movement of said trigger.

4. In a toy pistol using a strip carrying detonator, a mechanism carrying plate, a guide way formed with said plate parallel to the pistol top, a plunger movable in said guide way, a striking head formed therewith, an abutment intercepting said head, means for passing a detonator strip over said abutment, a spring impelling means for said plunger, a projection having a cam ledge on said plunger, a trigger having an

arm adapted to retract said plunger by contact with said cam ledge and a lug on said plate adapted to raise said trigger arm and release said plunger at the instant said trigger becomes fully rearwardly drawn, said arm passing over said cam ledge upon its return.

This specification signed and witnessed this 28th day of February, 1921.

CHARLES G. PALMER.
